SANITARY AND CLEANSING COMB

Louis Rembalinsky, Ridgewood, N. J., assignor of
one-half to Kirk Shivel, Ridgewood, N. J.

Application December 26, 1934, Serial No. 759,160

4 Claims. (Cl. 132—11)

My invention relates to a comb for general use, and more particularly for the use in barber shops, beauty parlors, and the like. Its object being to provide a comb which is inexpensive, yet more sanitary and having greater cleansing power over those already in use and one which is more particularly adapted for the removal of small hairs, dandruff, dust, grit, dirt, scabs, scales, oil and the like, from one's head after a cutting or trimming by a barber, hair-dresser or the like.

There is no comb at the present time which can remove all of the fine hairs from one's head after a cutting, and which is really sanitary. The present method is chiefly the use of a very fine tooth comb, which comb the barber uses on others. The present combs cannot pick up the fine hairs, due to their construction. My invention does eliminate such fine hairs from one's head. My comb is so inexpensive, that it can be discarded after use. It can also be used to great advantage after a shampoo to eliminate all the waste matter from one's head, such as small hairs, dust, grit, dandruff, dirt, scales, scabs, oil and the like. My invention is light, inexpensive and easy to handle, and does not require expert skill in order to accomplish its purpose.

My invention is principally made out of a paper composition. The teeth of said comb are evenly spaced at about the same spacing used in ordinary combs. However, there is provided between the teeth, of said comb and at the base thereof, a shoulder, wherein a fine soft material such as cotton, in sufficient quantities as to effectuate our purpose, may be inserted and may be fastened permanently to the comb. Said combs can be made of any length or thickness with various spacing of the teeth. They may be wrapped in cellophane paper, and may be made so cheaply, that they may be discarded after one use of each comb, thus making sure, that they are absolutely sanitary.

While my invention is preferably made out of a paper composition, together with the use of cotton, I do not intend to limit the scope of my invention to those materials, as one can readily see, that many other materials may be used in

the construction of the comb, and also in the construction of the filler, or cleansing part thereof, without departing from the scope of my invention.

I have illustrated the invention in one form only. I do not intend to limit myself to this particular method as it is apparent, that many other methods may be employed for obtaining the same result without departing from the scope of my invention.

My invention will be more clearly understood from the drawing, to which reference is now made.

Figure 1 is a perspective view of comb.

Figure 2 is an enlarged detail of Fig. 1.

Figure 3 is a cross-section on line 3—3 of Fig. 2.

Referring to Figures 1 and 3, one obtains an illustration of my invention in one form. Comb 10 has ordinary teeth 11, with a recess portion 12 formed at the base of the teeth to receive the absorbent material 13; shoulder 14 prevents the absorbent material from falling out and permits a tight packing of the absorbent material 13 as may be readily seen.

What I claim is:

1. In an article of manufacture, as described, a composite bar, stamped so as to form a comb containing straight teeth, said teeth being evenly spaced and containing a recessed portion and shoulder at the junction thereof, and an absorbent to fill said recess portion. 25

2. A comb, having straight evenly spaced teeth, 30 and having a recessed portion containing a shoulder at the junction of said teeth and an absorbent placed therein.

3. In combination a comb containing straight teeth being stamped from a composition, having evenly spaced teeth and containing at the junction of said teeth and between said teeth a recessed portion and shoulder and having placed in said recess an absorbent. 35

4. A comb stamped from cardboard, containing straight teeth, evenly spaced and having at the junction of said teeth and between said teeth a recessed portion and shoulder and having cotton placed in said recessed portion. 40
